UNITED STATES PATENT OFFICE.

FRANCIS A. STEVENS, OF SILVER LANE, CONNECTICUT.

DESIGN FOR A PARING-KNIFE.

49,528.

Specification for Design.

Patented Aug. 15, 1916.

Application filed May 16, 1916. Serial No. 97,946. Term of patent 3½ years.

To all whom it may concern:

Be it known that I, Mrs. FRANCIS A. STEVENS, a citizen of the United States, residing at Silver Lane, in the county of Hartford and State of Connecticut, have invented a new, original, and ornamental Design for Paring-Knives, of which the following is a specification, reference being had therein to the accompanying drawing.

Figure 1 is a side elevation of the complete knife, showing my design. Fig. 2 is a top plan view thereof.

I claim—

The ornamental design for a paring knife as shown.

In testimony whereof I affix my signature.

MRS. FRANCIS A. STEVENS.
